Francis B. Curtis,
BY Drake & Co., ATTYS.

UNITED STATES PATENT OFFICE.

FRANCIS B. CURTIS, OF EAST ORANGE, NEW JERSEY.

ELASTIC SUSPENDER-BUTTON FOR PANTS.

SPECIFICATION forming part of Letters Patent No. 351,497, dated October 26, 1886.

Application filed June 25, 1886. Serial No. 206,187. (No model.)

To all whom it may concern:

Be it known that I, FRANCIS B. CURTIS, a citizen of the United States, residing at East Orange, in the county of Essex and State of New Jersey, have invented certain new and useful Improvements in Elastic Suspender-Buttons for Pants; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to secure increased ease to the wearer, to avoid any unsightly appearance of the device when the same is applied to the garment, and to provide for sufficient durability and strength to resist the effects of ordinary wear and strain.

The invention consists in the arrangements and combinations of parts, substantially as will be hereinafter set forth, and finally embodied in the clauses of the claim.

25 Referring to the accompanying drawings, in which like letters indicate corresponding parts in each of the several figures, Figure 1 is a rear elevation of a portion of a pair of men's pants to which the improvements have been applied or in which they have been embraced or embodied. Fig. 2 is a section of the same, taken through line *x*. Figs. 3 and 4 are sectional views, and Fig. 5 a front or face view, of an elastic strap to which the suspender-button is secured, the last two figures showing a slightly varied construction.

In said drawings, A indicates a portion of a garment, particularly a pair of pants, to the rear of which has been secured in any ordinary manner the buckle and tongues *b b'* for taking up or tightening the waistband or portion of the garment. Near the upper edge of the garment are formed openings or perforations *c c*, through which straps *d d*, of elastic webbing or other elastic material, extend, said straps being secured on the inner side of the said garment by suitable rivets or stays, *e e*, and passing up through said openings to the outer side of the pants, where they are provided with the suspender-buttons *f*, said but-

tons being thus brought into the usual positions of suspender-buttons on the outside of the pants. The elastic portion of the straps are preferably of webbing, which is doubled over a pin or bar, *g*, and provided with an intervening layer or layers of india-rubber, *d'*, which increases the durability and strength of said strap materially. The buttons are preferably secured to a plate or plates, *h*, and the latter to the upper end of the webbing, as in Figs. 2, 3, and 4, as by this construction the buttons are held out firmly in a position convenient for the reception of the suspender. The stay *e*, for holding the strap to the pants, is arranged at a point where it is hidden from view by the tightening-straps *b'*. In view of the rivet or rivet-like device the strap may be secured by stitching; or other form of stay may be employed.

The plate *h*, upon which the button is secured, is preferably of two parts or of one piece doubled, at one end of which are formed jaws *h' h'*, between which the webbing or strap is secured, the said strap being preferably first turned over the rod or bar *g* and then inserted, together with the bar, between the jaws, and finally secured between said jaws by rivets *n*, which pass beneath said bar and hold it in place. By this construction there is but little danger of the strap being torn from the plate.

The pants are properly re-enforced at the stay *e*, and are otherwise formed or prepared to receive the straps in the manner described, the details of construction it being thought unnecessary to describe, as they may be varied as circumstances may dictate. However, I may add that I prefer to sew a tongue or piece, *k*, of strong cloth or fabric to the inner side of the pants just above the opening, as in Fig.

2. This extends down to and receives the stay, so that the draft thereon is transmitted to the pants above the opening, and the latter is thus prevented from spreading and the pants from sagging, as will be understood.

Having thus described the invention, what I claim as new is—

1. The combination, with men's pants perforated at or near the waistband, of suspender-buttons secured on elastic straps, which latter are secured on the inner side of the garment

and extend through the perforation to the outer side of the pants, substantially as set forth.

2. The combination, with an elastic strap, 5 of a plate, *h*, button *f*, and pin or bar *g*, and rivets *n*, all said parts being arranged and combined and adapted to operate in connection with men's pants, substantially as and for the purposes set forth.

In testimony that I claim the foregoing I do hereby have hereunto set my hand this 24th day of June, 1886.

FRANCIS B. CURTIS.
